SYSTEM FOR SILENCING RADIO RECEIVERS DURING AUTOMATIC TUNING THEREOF

Filed Dec. 15, 1937

UNITED STATES PATENT OFFICE

2,331,039

SYSTEM FOR SILENCING RADIO RECEIVERS
DURING AUTOMATIC TUNING THEREOFDonald H. Mitchell, Chicago, Ill., assignor to
Galvin Manufacturing Corporation, Chicago,
Ill., a corporation of Illinois

Application December 15, 1937, Serial No. 179,972

10 Claims. (Cl. 250—20)

This invention relates to radio receiving sets and especially to circuits for sets in which tuning is accomplished by a tuning motor, with said circuits acting to provide silent tuning in a set by such motor. The invention, furthermore, relates broadly to the use of a tertiary winding on an electrode motor in a radio receiving system, for providing a voltage output from the motor windings acting as a transformer, which voltage varies, either greater or less, from the voltage supplied to the motor for energization thereof. This source of supply may be used for operating electrical indicators for the receiver, and other purposes, as well as providing silent tuning for the radio receiver as will be more fully described hereinafter.

Receiving sets with automatic tuning have now become quite common. Some of these sets operate by means of a tuning motor which, in response to pressing a button or the like corresponding to a particular predetermined station, is energized and will turn the tuning condensers of the set to the proper setting for that station. When the set is thus receiving one station as desired, another button may be pressed and the motor will turn the condensers to change the tuning of the set from the one station to another station corresponding to such other button. If broadcast stations intervened between the two stations, these intervening stations would be brought in and heard momentarily as their frequencies were crossed by the tuning condensers. Inasmuch as normal operating volume is maintained on the receiver during such tuning, such stations would be brought in with an objectionable blast of sound. It is even worse, however, if the set is provided with automatic frequency control which operates independently of the tuning condensers to correct, within limits, any imperfect tuning. This automatic frequency control, because of its corrective effect, tends to seize any station which is received with sufficient strength to make such automatic frequency control effective and pull such station into peak tuning as the condensers are rotated over the broadcast band. The result is that if the desired predetermined station to which the receiver is being tuned is close to a strong station the automatic frequency control might retain the wrong station and prevent reception from the desired station.

An object of my invention is to provide in a radio receiving system having an electric motor therein, in effect, a new source of voltage of a different value than that supplied to the mo-

tor for operating and indicating purposes in the radio receiver system.

A further object of my invention is to provide silent accurate tuning of a radio receiver when utilizing a motor for such tuning.

A still further object of the present invention is to prevent all noise during tuning and simultaneously to prevent the automatic frequency control from working improperly.

One of the features of my invention is the provision of a tertiary winding on a tuning motor for a radio receiver to cause the production of an induced voltage therein for subsequent rectification to be used to bias the first audio tube and stop the passage of signals therethrough, and to be used to simultaneously substantially stifle the A. F. C. action.

Additional objects and features will be apparent from the following description and from the drawing, in which the figure is a diagrammatic illustration of the radio receiving set chosen for illustration of this invention, the features of the circuit to which this invention particularly relates being shown in greater detail than the remainder of the circuit.

In the form of the invention chosen for illustration the main portion of the radio receiving set has been illustrated very diagrammatically, merely indicating the passage of the signal from the aerial 11 through the successive stages of amplification, each of which is appropriately marked in the drawing. Each of the various stages has been shown diagrammatically as a box rather than as a tube to indicate the inclusion of other elements such as the tuning circuits. The signals are first amplified at radio frequency, this stage being marked "R. F." in the drawing. Then the radio frequency signals are mixed at the "mixer" with a different frequency generated within the set by an oscillator, which may include the mixing tube or a separate tube, to produce a beat of predetermined frequency, called the intermediate frequency. These signals of intermediate frequency are amplified twice, first at the point marked "1st I. F." and then at the point marked "2nd I. F." in the drawing. Next the signals are rectified by the diode detector, which in effect removes the intermediate frequency, leaving only the audio frequency. The audio frequency waves are amplified twice, once at the point marked "1st audio" and then by the output. Thereafter, the signals are impressed on the loud speaker 14, which converts them into sound waves.

The tube has been shown within each of the boxes labeled "1st I. F." and "1st audio" and the omission of conventional elements in the grid connections have been indicated by dotting these connections. The conventional connections for other tube elements have been left incomplete.

The illustrated receiving set is provided with automatic volume control, which tends to maintain a predetermined signal strength at the 2nd I. F. stage by automatically controlling the amplification of the received signals. Since the automatic volume control per se is not part of this invention it will be explained only to the extent necessary to an understanding of the present invention where it appears in the complete circuit combination. An appropriate connection 16 is made on the output side of the 2nd I. F. stage and is connected with a condenser 18, which may be 150 mmf. The condenser 18 is connected to diodes 20, in the 1st audio tube 22, which have the effect of rectifying the voltage transmitted through the condenser 18 so that only a negative voltage is transmitted through the automatic volume control lead 24, which extends back to the R. F. and mixer stages to increase their negative grid bias for the purpose of controlling their gain and hence controlling the resulting signal strength. The effect, stated previously, is that an undesirably high signal strength at the 2nd I. F. stage is effective through the automatic volume control lead 24 to impress a negative bias on the control grids in the earlier amplifying stages to reduce the amplification of the stages. Modulations corresponding to sound waves may be by-passed by condenser 25, one suitable value for which is .03 microfarad.

The illustrated receiving set is also provided with automatic frequency control in which a lead 26 extends from an appropriate connection in the diode detector stage to a control unit 12 to alter the frequency of the oscillations enough to compensate for any imperfect adjustment of the tuning condensers so as to make the intermediate frequency that for which the intermediate frequency stages are designed. As previously stated, one effect of this automatic frequency control is to cause the set to retain a station once received, even though the tuning condensers are turned slightly to the setting for a different station. In other words, as the tuning condensers are being turned to receive a relatively weak station just beyond a strong station, the automatic frequency control would tend to seize the strong station as it was passed and not release it to receive the adjacent weak station.

According to the present invention this undesirable effect is prevented by temporarily reducing the sensitivity of the receiver during tuning to such an extent that the automatic frequency action will not begin until a station has actually been tuned in. Automatic frequency control, of course, is desirable for obtaining peak tuning when properly utilized. On automatic tuning, however, it is objectionable during such tuning as described above. The signal strength is reduced to prevent this effect by applying a special negative voltage to the automatic volume control lead 24, this voltage having the same effect as the voltage normally applied to the lead 24 but to a greater degree. The special voltage referred to is derived from a third winding 30 on the tuning motor, the third winding being in inductive relation to the main winding 32 and to the reverse winding 34. Whenever either of these windings are energized in response to press-

ing a tuning button or the like for closing the supply circuit for the motor, a voltage is induced in the third winding 30. Of course, the motor begins to operate in response to such energization immediately. The voltage provided may be in the neighborhood of 60 or 80 volts, but is alternating and must therefore be rectified. To this end the third winding 30 is connected to a condenser 36 which may be of .1 microfarad capacity, which in turn is connected by wire 37 to a plate 38 in the 1st I. F. tube 40. For convenience of distinction from the main plate 42 in this tube, this plate may be called a diode. The wire 37 is connected to condenser 44, the other side of which is connected to the other diode 46 by wire 48. The result of this connection is that when an alternating voltage is applied by the winding 30 to the condenser 36, the voltage on wire 37 is substantially rectified and another rectified voltage is impressed on wire 48. This voltage is applied by wire 49 to the automatic volume control lead 24. The wire 48 is preferably connected between resistances 50 and 52 which comprise part of the automatic volume control system. In one form of the invention found satisfactory the resistances 50 and 52 may each be $\frac{1}{4}$ megohm. It should also be noted that the resistance 52 is connected to the power supply unit of the set through lead 54 and to ground through a resistance 56 which provides a proper negative grid bias. One value for the resistance 56 found suitable is 33 ohms.

Although the effect of applying a special negative voltage to the automatic volume control system, as above described, reduces the signal strength sufficiently to prevent the automatic frequency control from operating to seize a frequency being crossed during tuning, it does not reduce the signal strength sufficiently to completely eliminate sound as strong stations are crossed. To this end an additional muting circuit is added. The wire 37 extending between the condenser 36 and the diode 38 is connected by a wire 60 through resistances 61 and 62 to the grid 64 of the 1st audio frequency tube 22. The result is that when voltage is induced in the third winding 30 of the tuning motor, this voltage, rectified by the diodes 38 and 46, is applied as a negative grid bias to the grid 64. The constants of the set should be such that this bias is a cut-off bias, reducing the gain of the tube substantially to zero. With the set illustrated this result was accomplished by making the resistances 61 and 62, respectively, .470 megohm and one megohm, the condenser 66 being .1 microfarad, and the resistance 67 being .220 megohm.

It should be observed that because of the condenser 44 isolating the diodes 38 and 46 the voltage applied to the automatic volume control lead 24 and to the audio grid 64 may be independently controlled by varying the resistances associated with each diode, particularly the load resistances 52 and 67.

It has been very difficult heretofore to completely silence a radio receiving set merely by automatically operating electrical circuits. This has been accomplished in the present instance by combining two different muting effects to temporarily render the set substantially inoperative while such set is being tuned. First is the muting effect of the negative voltage impressed on the automatic volume control lead 24, which greatly reduces the signal strength reaching the 1st I. F. stage of amplification,

The second muting effect is the application of a cut-off bias to the grid 64 of the 1st audio frequency tube 22, which should cut the gain to zero at this point. This combination of the two muting effects controlled jointly, simultaneously and automatically by the third winding 30 when the tuning motor is operated, will render the receiving set completely silent even though it was formerly operating with high volume output.

It is thus seen from the above description that I provide a very simple and inexpensive means in a radio receiver system employing an electric motor for supplying voltage to the receiver system different in value than that for the source of supply to such motor. The transformer action with the third winding may be suitably employed to provide a larger or smaller voltage than that for the motor, and as previously mentioned, this may be used for the purpose of lighting a tuning indicating lamp, for instance, for other types of operating indication in the receiver system, as well as for silent tuning as above more particularly described. The constants, such as resistance or condenser values which have been given heretofore, are merely illustrative. Widely different values may be found entirely satisfactory and with different receiving sets will probably be necessary. These values are given as examples of values which have been found satisfactory in commercial embodiments of the invention.

The disclosures of this application are illustrative and the invention is not to be limited by them. In fact, if modifications or improvements are not at once obvious, they may be devised in the course of time to make additional use of the broad ideas taught and covered by this application.

I claim:

1. A radio receiver system including in combination, a radio receiver and an electric motor for directly driving tuning means for said radio receiver, said driving motor including a main field winding, a reversing field winding and a tertiary winding in inductive relation with said main field and reversing windings, a source of voltage for said motor, with said tertiary winding in said driving motor acting to provide an alternating voltage output therefrom, means in said radio receiver for rectifying said voltage output from said tertiary winding, and means for utilizing said rectified voltage for silencing said radio receiver during the tuning operation of said driving motor.

2. A system for rendering a radio receiver circuit having an audio tube and an automatic volume control network substantially inoperative during the tuning thereof by an electric motor, including in combination means for developing an induced voltage at said motor upon energization of said motor, means for rectifying said voltage, means for utilizing a portion of said rectified voltage to bias said audio tube and reduce its gain, and means for applying another portion of said rectified voltage to the automatic volume control network of said receiver to reduce the sensitivity of said receiver.

3. A radio receiving set provided with a tuning motor, characterized by the provision of means for silencing the set during operation of the tuning motor, said means comprising a third winding in inductive relationship with the motor to be energized when the motor is energized, rectifying means connected with the third winding, muting means connected with the rectify-

ing means and effective at the preliminary stages of amplification, and another muting means connected with the rectifying means and effective in an audio stage of amplification for further muting the set.

4. A radio receiving set having an automatic volume control circuit, an automatic frequency control circuit, and a tuning motor, characterized by the provision of a third winding for the tuning motor in inductive relation thereto whereby voltage is induced in the third winding when the motor is energized, means for rectifying the voltage, means for applying the rectified voltage to the automatic volume control circuit for reducing the signal strength at the point where the signals govern the automatic frequency control sufficiently to render the automatic frequency control circuit ineffective to seize a frequency being crossed in tuning, and means for applying the rectified voltage as a cut-off bias on the grid of an audio frequency amplifying tube.

5. A radio receiving set having an automatic frequency control circuit, and a tuning motor, characterized by the provision of a third winding for the tuning motor in inductive relation thereto whereby voltage is induced in the third winding when the motor is energized, means for rectifying the voltage, and means for applying the rectified voltage to a grid of an amplifying tube in advance of the automatic frequency control circuit for reducing the signal strength at the point where the signals govern the automatic frequency control sufficiently to render the automatic frequency control circuit ineffective to seize a frequency being crossed in tuning.

6. A radio receiving set having an automatic volume control circuit, an automatic frequency control circuit, and a tuning motor, characterized by the provision of a third winding for the tuning motor in inductive relation thereto whereby voltage is induced therein when the motor is energized, means for rectifying the voltage, and means for applying the rectified voltage to the automatic volume control circuit for reducing the signal strength sufficiently to render the automatic frequency control circuit ineffective to seize a frequency being crossed in tuning.

7. A radio receiving set having an automatic volume control circuit, an automatic frequency control circuit, and a tuning motor, characterized by the provision of a third winding for the tuning motor in inductive relation thereto whereby voltage is induced therein when the motor is energized, means for rectifying the voltage, means for applying the rectified voltage to the automatic volume control circuit for reducing the signal strength sufficiently to render the automatic frequency control circuit ineffective to seize a frequency being crossed in tuning, and means for applying the rectified voltage as a cut-off bias on the grid of an audio frequency amplifying tube, the rectifying means comprising a pair of diodes within a vacuum tube, electrically separated by a condenser, whereby the rectified voltage produced with the aid of each diode may be independently predetermined, one diode being connected to the automatic volume control circuit and the other to the audio grid.

8. A radio receiving set including an amplifying vacuum tube having a grid, a tuning motor, and means acting entirely electronically for muting the set during operation of the tuning motor, including an independent energizing winding on the motor for producing an alternating voltage during operation of the motor, rectifying

means for rectifying the voltage, and means for applying the rectified voltage to said grid as a gain reducing bias.

9. Radio apparatus including a radio receiver circuit having tuning means and including an audio tube therein having a grid, a driving motor for operating the tuning means for said radio receiver circuit, said motor having means including an independent energizing winding thereon for supplying an alternating voltage to said receiver circuit during operation of the motor, means for rectifying said alternating voltage, and means for applying the rectified voltage to the grid of said audio tube to bias said tube and render the same inoperative for amplifying a sig- 15

nal therethrough during operation of said driving motor.

10. Radio apparatus having movable means and including a plurality of tubes in electrical connection in said apparatus, a rotary driving motor operatively connected to said movable means to drive the same and including a field winding, said motor having another winding thereon in inductive relation to said field winding for producing an operating voltage during rotation of said motor in driving said movable means, and means coupling at least one of said tubes with said other winding.

DONALD H. MITCHELL.
